UNITED STATES PATENT OFFICE.

JERRY H. SCHIERLOH, OF OAKWOOD, NEAR DAYTON, OHIO, ASSIGNOR TO THE DAYTON STENCIL WORKS COMPANY, OF DAYTON, OHIO, A CORPORATION OF OHIO.

DESIGN FOR A METAL TRADE TOKEN.

Application filed January 24, 1927. Serial No. 20,476. Term of patent 14 years.

To all whom it may concern:

Be it known that I, JERRY H. SCHIERLOH, a citizen of the United States, residing at Oakwood, in the county of Montgomery, near the city of Dayton, State of Ohio, have invented a new, original, and ornamental Design for a Metal Trade Token, of which the following is a specification, reference being had to the accompanying drawing, forming part hereof.

Figure 1 is a front view and Figure 2 an edge view of a metal trade token, showing my new design.

I claim:

The ornamental design for a metal trade token, as shown.

JERRY H. SCHIERLOH.
